UNITED STATES PATENT OFFICE.

LESTER S. KUBIAC, OF YOUNGSTOWN, OHIO, ASSIGNOR TO THE PHOTOCOGENIC MACHINE COMPANY, OF YOUNGSTOWN, OHIO, A CORPORATION OF OHIO.

CARBON CONTROL FOR ARC LAMPS.

Application filed August 26, 1925, Serial No. 52,538. Renewed July 9, 1928.

My invention pertains to electric arc lamps, the primary object being to provide economic and efficient mechanism for moving both the positive and negative carbons longitudinally, 5 when disposed in planes angular to each other, and is designed more particularly for lamps to be used when it is desired to project the rays of light in a certain direction and concentrate them upon a specific object.

10 To this end I employ connecting mechanism between the carriers of the two carbons, which is adapted to move the negative carbon longitudinally in absolute synchronism with a similar movement of the positive carbon 15 when the latter is actuated by suitable electrical control.

Figure 1 is a side elevation; Figure 2 is a top plan view; and Figure 3 is a vertical sectional view on line 3—3 Figures 1 and 2.

20 Similar reference characters designate corresponding parts throughout the various figures of the drawings.

1 represents the base or bed plate, to which are rigidly secured three standards or uprights 2, 3 and 18, 2 being at one end, 3 intermediate the ends and 18 at the opposite end.

25 Each of the standards 2 and 3 is provided at its outer end with openings 2' and 3' for the reception of rods 4 and 4', respectively, and in which these rods are securely fastened.

30 Slidably mounted upon rods 4 and 4' is the carbon carrier 5, provided with a central opening in which the positive carbon 6 is held in any desired adjusted position by

35 screw 7.

Rigidly secured to the outer face of the standard 3, and at its outer end, is the plate *p*, provided with a central opening which serves as a guide for the positive carbon 6.

40 Integrally formed with the carrier 5 is the depending lug 8, carrying the pin 9. Also connected with the lug 8 is the positive wire 10 of the electric circuit, leading through the binding post 11 and wire 12 to the electrical

45 source.

Also rigidly secured to the base 1 is the upstanding lug or bracket 13, upon which is mounted gear 14 by bolt or journal 15. Rigidly secured to gear 14 is the arm 16, provided 50 at its outer or swinging end with a forked terminal, the opposite arms or branches 17—17 of which are adapted to embrace the pin 9 carried by the lug 8.

Mounted upon the journal 15 of the gear

14 is a helical spring 35, which is housed or seated in the recess 36 in the face of gear 14 (see Figure 3).

The standard 18 is provided at its outer end with openings 19 and 19' for the reception of the oppositely disposed rods 20 and 20'.

Carried by the upright or standard 3 is the bracket 21, provided at its outer end with openings to serve in connection with openings 19 and 19' in standard 18 for the reception of rods 20 and 20', and in which these rods are securely fastened.

Slidably mounted upon rods 20 and 20' is the carbon carrier 22, provided with a central opening in which the negative carbon 23 is held in any desired adjusted position by screw 24.

Secured to the outer face of the bracket 21 is the plate 25, provided with a central opening which serves as a guide for the negative carbon 23.

Integrally formed with the carbon carrier 22 is the depending lug 26, carrying the pin 27. Also secured to lug 26 is the negative wire 28 of the electric circuit, leading through the solenoid to the electrical source.

Also rigidly secured upon base 1 is the upstanding lug or bracket 29 upon which is mounted gear 30, which carries upon its face a circular boss or hub 31, provided with circumferential ratchet teeth.

Swingingly mounted upon the journal of gear 30 is the arm 32 provided at its outer end with a forked terminal, the opposite arms or branches 33—33 of which embrace the pin 27 carried by the lug 26. This arm is provided intermediate its ends with a longitudinal slot 34, in which is mounted a spring controlled slide 34' carrying at one end a ratchet or pawl adapted to engage the teeth of hub 31, for the purpose of locking the arm 32 and gear 30 to move in unison.

The operation of my device is as follows: When the positive carbon 6 is actuated by electrical energy, causing it to move longitudinally, it will swing the outer end of arm 16 in the same direction, thereby setting in motion gears 14 and 30 and causing the arm 32 to swing in the direction necessary to actuate the carbon carrier 22 to move the negative carbon 23 longitudinally, either toward or away from the point of the arc, as the positive carbon may be moving.

The tension of spring 35 on journal 15 of gear 14 tends to draw the point of the opposing carbons together, and for the purpose of establishing the arc the points of the two carbons are separated through electrical energy overcoming the resistance of the spring.

When renewing the carbons, after placing the negative carbon 23 in its carrier 22, the arm 32 may be moved to the proper adjustment position by releasing the ratchet or pawl from the teeth of the hub 31.

I claim:

1. In an electric arc lamp, the combination with two carbons, mounted in planes angular 15 to each other, of a slidably mounted carbon carrier for each carbon, a rocker-arm loosely connected at its swinging end with one of said carriers and carrying at its opposite end a gear, a rocker-arm loosely connected at its 20 swinging end with the other carrier, a gear mounted at the opposite or pivotal end of said rocker-arm and provided on its face with a boss or hub having circumferential ratchet teeth, and a locking member slidably mounted 25 upon said rocker-arm and carrying at one end a pawl or dog adapted to engage said

ratchet teeth, said two gears being adapted to intermesh.

2. In an electric arc lamp, the combination with two carbons, mounted in planes angular 30 to each other, of a slidably mounted carbon carrier for each carbon, a rocker-arm loosely connected at its swinging end with one of said carriers and carrying at its opposite end a gear, said gear being provided in its face 35 with a recess having a helical spring housed therein, one end of said spring being attached to said gear and the other end to the journal thereof, a rocker-arm loosely connected at its swinging end with the other carrier, a gear mounted at the opposite or pivotal end of said rocker-arm and provided on its face with a boss or hub having circumferential ratchet teeth, and a locking member slidably mounted 40 upon said rocker-arm and carrying at one end a pawl or dog adapted to engage said ratchet teeth, said two gears being adapted to intermesh.

In testimony whereof, I have hereunto affixed my signature.

LESTER S. KUBIAC.
